UNITED STATES PATENT OFFICE

AIRSHIP

Application April 21, 1936, Serial No. 75,622

(CL. 244—125)

This invention relates to new and useful improvements in lighter than air ships of the so-called dirigible or Zeppelin type and more particularly to the framework or body structure of such ships.

Up to the present time, the frame or body structures of the majority of lighter than air ships of the general type set forth, have been characterized by their extreme rigidity, a factor which is believed by many persons to have been responsible for numerous disasters and wrecks because of the relatively great surface area of ships of this type and the practical inability of constructing the frames or body structures thereof with sufficient strength to withstand the constantly varying, unequal stresses and strains to which such ships are subjected by the force of direct and counter air currents and other elements of nature.

The principal object of this invention therefore, is to provide a sectional frame or body structure for lighter than air ships of the character set forth which is novelly constructed to afford a predetermined limited degree of flexibility or relative movement between adjacent sections or units of said body structure and arranged to withstand the initial impact of sudden stresses and strains due to the force of direct and counter air currents as well as other elements of nature and absorb and distribute such stresses and strains throughout the frame or body structure so that the full force of such currents will not be permitted to concentrate within a relatively small portion of the surface area of the ship and thus cause the frame or body to buckle or crumple due to the differential in such force or pressure within that portion and the remainder of the surface area of the ship.

Another object of the invention is to provide a frame or body structure for lighter than air ships of the stated character which is constructed and arranged to absorb, distribute and dissipate throughout the frame structure not only the force and impact of direct stresses and strains but also those forces of nature which react to subject the frame structure or parts thereof to torsional or twisting stresses and strains.

Another object of the invention is to provide a frame or body structure of the character set forth for lighter than air ships of the stated type which is capable of successfully withstanding comparatively greater direct and torsional stresses and strains than has been possible heretofore in ships of this character having rigid frame or body structures.

The above and other objects of the invention are set forth in detail in the following specification and in the drawings which illustrate the principles of the invention.

Referring now more particularly to the drawings, reference numeral 1 designates generally a lighter than air ship of the dirigible or Zeppelin type having a frame or body structure 2 encased within a covering 3 and including the customary passenger gondola 4 as well as the usual elevators and rudders 5 and 6 respectively. The frame or body structure 2 is composed of a plurality of more or less similarly constructed units or sections 7 arranged end to end in axial alignment.

Each unit 7 is provided with a base 8 which is rigidly connected to the frame or body structure 2.

Each base 8 is provided with a plurality of legs 9 which are arranged in a generally vertical alignment and which are rigidly connected to the frame or body structure 2.

Each leg 9 is provided with a plurality of feet 10 which are rigidly connected to the frame or body structure 2.

Each foot 10 is provided with a plurality of toes 11 which are rigidly connected to the frame or body structure 2.

Each toe 11 is provided with a plurality of claws 12 which are rigidly connected to the frame or body structure 2.

Each claw 12 is provided with a plurality of points 13 which are rigidly connected to the frame or body structure 2.

Each point 13 is provided with a plurality of tips 14 which are rigidly connected to the frame or body structure 2.

Each tip 14 is provided with a plurality of claws 15 which are rigidly connected to the frame or body structure 2.

Each claw 15 is provided with a plurality of points 16 which are rigidly connected to the frame or body structure 2.

Each point 16 is provided with a plurality of tips 17 which are rigidly connected to the frame or body structure 2.

Each tip 17 is provided with a plurality of claws 18 which are rigidly connected to the frame or body structure 2.

Each claw 18 is provided with a plurality of points 19 which are rigidly connected to the frame or body structure 2.

Each point 19 is provided with a plurality of tips 20 which are rigidly connected to the frame or body structure 2.

Each tip 20 is provided with a plurality of claws 21 which are rigidly connected to the frame or body structure 2.

Each claw 21 is provided with a plurality of points 22 which are rigidly connected to the frame or body structure 2.

Each point 22 is provided with a plurality of tips 23 which are rigidly connected to the frame or body structure 2.

Each tip 23 is provided with a plurality of claws 24 which are rigidly connected to the frame or body structure 2.

Each claw 24 is provided with a plurality of points 25 which are rigidly connected to the frame or body structure 2.

Each point 25 is provided with a plurality of tips 26 which are rigidly connected to the frame or body structure 2.

Each tip 26 is provided with a plurality of claws 27 which are rigidly connected to the frame or body structure 2.

Each claw 27 is provided with a plurality of points 28 which are rigidly connected to the frame or body structure 2.

Each point 28 is provided with a plurality of tips 29 which are rigidly connected to the frame or body structure 2.

Each tip 29 is provided with a plurality of claws 30 which are rigidly connected to the frame or body structure 2.

Each claw 30 is provided with a plurality of points 31 which are rigidly connected to the frame or body structure 2.

Each point 31 is provided with a plurality of tips 32 which are rigidly connected to the frame or body structure 2.

Each tip 32 is provided with a plurality of claws 33 which are rigidly connected to the frame or body structure 2.

Each claw 33 is provided with a plurality of points 34 which are rigidly connected to the frame or body structure 2.

Each point 34 is provided with a plurality of tips 35 which are rigidly connected to the frame or body structure 2.

Each tip 35 is provided with a plurality of claws 36 which are rigidly connected to the frame or body structure 2.

Each claw 36 is provided with a plurality of points 37 which are rigidly connected to the frame or body structure 2.

Each point 37 is provided with a plurality of tips 38 which are rigidly connected to the frame or body structure 2.

Each tip 38 is provided with a plurality of claws 39 which are rigidly connected to the frame or body structure 2.

Each claw 39 is provided with a plurality of points 40 which are rigidly connected to the frame or body structure 2.

Each point 40 is provided with a plurality of tips 41 which are rigidly connected to the frame or body structure 2.

as shown, and in the present instance each of said frame or body sections 7 includes relatively spaced end and intermediate polygonal frame portions 8 and 9 respectively. The end frame portions 8 are each composed of a plurality of structural girders or like members 10, the ends of each of which are secured in any suitable manner such as by welding, riveting or the like, to the adjacent outer surfaces of the inwardly extending side or wall portions 11 of a plurality of triangular caps or like members 12 disposed in alternate relation between adjacent members 10 peripherally of said end portions as shown in Figs. 2 and 4 of the drawings.

15 A number of other structural members 13 such as girders, beams or the like are secured in a similar manner to the outer surfaces of the previously mentioned inwardly extending side or wall portions 11 of certain of the cap members 12 and the ends of said members 13 are notched or otherwise formed to receive the opposite corners at the base or inner end edge of said cap members in the manner shown, said structural members 13 being braced or supported with respect to the 20 intermediate cap members 12 by means of tubular or other struts 14 which are secured between the inner side or wall portion 11 of the caps 12 and the members 13 in any suitable manner such as by welding, riveting, or the like. Still other members 15 similar to the previously described structural members 13 have their ends secured in the foregoing manner to the inner faces of adjacent members 13 inwardly from the ends thereof as shown, and a plurality of wires, ropes or cables 30 16 extend radially of the end frame portions of the units or sections 7 at equally spaced intervals thereabout, said cable or wires 16 being connected between a central ring member 17 and the previously mentioned structural members 15 and having springs or other resilient elements 18 located intermediate their ends for the purpose of adding flexibility to the structure.

The previously mentioned intermediate frame portion 9 of each unit or section 7 is constructed 45 in accordance with the foregoing description of the end frame portions 8 thereof with the exception that the triangular cap members 12 as well as the ropes or cables 16 of the latter are not present in the former and the ends of the 50 peripheral structural elements or members 10 are secured directly together in abutting relation. The outer or end frame portions 8 as well as the intermediate portion 9 are supported in relatively spaced coaxial relation with respect to each other 55 by means of longitudinally disposed triangular structural members 19 which have their outer ends inserted into the recess formed by the inwardly extending wall portions 11 of the cap members 12 in the end portions 8 of each frame section 7 so that said wall portions 11 embrace the end portions of said members 19.

60 Referring now particularly to Figs. 5 and 6 of the drawings, it will be observed that the so-called cap members 12 are provided with braces or supports 20 of substantially semi-circular configuration which abut the inner surface of the triangular base or end portion 21 thereof and are secured to angle pieces or the like 22 in any suitable manner such as by welding or the like, said angle pieces engaging portions of the inner surfaces of the ends of the longitudinal structural members 19 and being secured thereto and to the side or wall portions 11 of said caps 12 by means 65 of rivets or the like 24, although any other means

of securing these elements together may be employed.

After the desired number of units or sections 7 have been constructed in accordance with the foregoing, the several sections are arranged coaxially end to end with the several co-planar outer base or end faces 25 of the member 12 of each of said sections in alignment with one another and the opposite ends of one or more coil springs or other similar resilient elements 26 of substantial capacity are permanently secured in any suitable manner such as by welding or the like, to said correspondingly aligned outwardly facing surfaces 25 in adjacent end portions 8 of each of said unit or frame sections 7 in the manner and relation shown in Figs. 4, 5 and 6 of the drawings hereof, whereby successive adjacent units or sections 7 composing the frame or body structure 2 of the ship are securely and firmly connected together yet a certain degree of flexibility or resiliency exists between each adjacent section thereof.

In certain instances it may be undesirable or impractical to secure opposite ends of the several springs or like resilient elements 26 directly to the outer end or base faces 25 of the cap members 12 in which event the ends of said resilient elements 26 may be permanently secured in any suitable manner to or within supports, sockets or the like 27, for example as indicated at 29 in Fig. 7 of the drawings, said supports, sockets or the like 27 being in turn secured to said faces 25 of said cap members 12 by means of rivets, welding or any other suitable means.

By constructing the frame or body structures 2 of lighter than air ships in accordance with the foregoing description the undesirable extreme rigidity of such structures is eliminated and the framework rendered more or less flexible and resilient so that it will yield slightly to the initial impact or shock of stresses and strains and other forces without rending or crumpling the structural elements thereof. The initial force of the shock due to stresses and strains is absorbed in part at the point of impact by relative expansion and contraction of the spring 26 at the nearest resilient connections between the longitudinally extending members 19 of the sections and the remainder distributed and similarly absorbed by the resilient connections between the members 19 of the frame sections extending longitudinally of the ship at either side of said point of impact. After the initial shock upon the structure has been distributed and absorbed in this manner by the resilient connections between the longitudinal members of the frame sections, the body structure will recover and effectively withstand the force of the stress or strain as long as it continues. The reaction of the body structure to torsional stresses and strains is substantially the same, the initial impact of the force being absorbed proportionally by the resilient elements 26 between and adjacent the peripheries of the end portions 8 of the sections 7 affected.

It will be observed from the foregoing that the full force and effect of any stress or strain exerted on the body structure 2 is not permitted to concentrate within a relatively small fraction of the total surface area of the ship but is distributed longitudinally and circumferentially throughout the said body structure by the several rigid structural members therein and absorbed and spent proportionally by the reaction of the resilient connections between the longitudi- 75

dinal members of the several sections 7 of said structure which function to resist and strengthen the latter by virtue of the relative expansion and contraction of said resilient elements. The present construction further functions to eliminate the possibility of the occurrence of small fractures and breaks at various points throughout the body structure as well as the tendency toward crystallization of the material of the component structural elements as the result of the day to day wear caused by contact with the elements of nature.

While the structural members 10 and 19 of the several sections or units 7 as well as the so-called cap members 12 have been illustrated and described as being of substantially triangular shape, it will be obvious that the invention is not limited to structural elements of any particular form or configuration but the same may be of any shape desired, it being preferred, however, to have the cross section shape of the several longitudinal members 19 correspond to the shape of the cap members employed in a particular body structure so that the end portions of said members 19 may be snugly embraced by the inwardly extending side or wall portions 11 of said cap members in accordance with the previous description, and it is to be further understood that although a specific embodiment of the invention has been set forth herein for purposes of description, it is not intended that said invention shall be limited precisely thereto but that various methods of construction may be employed in the basic frame structure and resilient connections provided therebetween without departing from the invention where such changes, modifications and alterations reside within the scope of the annexed claims.

I claim:

1. A skeleton framework for airships including a plurality of substantially equally spaced circumferentially arranged articulated composite beams extending along the surface of said framework from end to end thereof and composed of a succession of aligned rigid members flexibly connected together by means capable of absorbing tension, compression and torsional stresses whereby stresses and strains received by the framework are transmitted and distributed longitudinally thereof by said members and absorbed and spent in said connecting means.

2. A skeleton framework for airships including a plurality of substantially equally spaced circumferentially arranged parallel groups of aligned rigid structural members extending along the surface of said framework at predetermined spaced intervals longitudinally thereof, a plurality of spaced parallel groups of circumferentially extending rigid structural members secured between the corresponding longitudinal structural members in each adjacent parallel group thereof, means secured to the ends of each longitudinal member in the several parallel groups thereof constructed and arranged to provide an outwardly facing plane surface at opposite ends of each of said members, and means capable of absorbing tension, compression and torsional stresses connecting the plane surfaces of the first mentioned means at adjacent ends of each of said longitudinal members whereby stresses and strains received by the framework are transmitted and distributed longitudinally and circumferentially thereof by said structural members and absorbed and spent in said connecting means.

3. A skeleton framework for airships including

a plurality of substantially equally spaced circumferentially arranged parallel groups of aligned rigid structural members extending along the surface of said framework at predetermined spaced intervals longitudinally thereof, means secured to the ends of each longitudinal member in the several parallel groups thereof constructed and arranged to provide an outwardly facing plane surface at opposite ends of each of said members, and means capable of absorbing tension, compression and torsional stresses connecting the plane surfaces of the first mentioned means at adjacent ends of each of said longitudinal members whereby stresses and strains received by the framework are transmitted and distributed longitudinally thereof by said members and absorbed and spent in said connecting means.

4. A skeleton framework for airships including a plurality of substantially equally spaced circumferentially arranged parallel groups of aligned rigid structural members extending longitudinally in the surface of said framework at predetermined spaced intervals, a plurality of spaced parallel groups of circumferentially extending rigid structural members secured between the corresponding longitudinal structural members in each adjacent parallel group thereof, means secured to the ends of each longitudinal member in the several parallel groups thereof constructed and arranged to provide an outwardly facing plane surface at opposite ends of each of said members, and coiled means capable of absorbing tension, compression and torsional stresses having its opposite ends connected respectively to the plane surfaces of the first mentioned means at adjacent ends of each of said longitudinal members whereby stresses and strains received by the framework are transmitted and distributed longitudinally and circumferentially thereof by said structural members and absorbed and spent in said connecting means.

5. A skeleton framework for airships including a plurality of substantially equally spaced circumferentially arranged parallel groups of aligned rigid structural members extending longitudinally in the surface of said framework at predetermined spaced intervals, means secured to the ends of each longitudinal member in the several parallel groups thereof constructed and arranged to provide an outwardly facing plane surface at opposite ends of each of said members, and coiled means capable of absorbing tension, compression and torsional stresses having its opposite ends connected respectively to the plane surfaces of the first mentioned means at adjacent ends of each of said longitudinal members whereby stresses and strains received by the framework are transmitted and distributed longitudinally thereof by said members and absorbed and spent in said connecting means.

6. A framework for airships including a plurality of articulated composite beams extending in the surface of the framework from end to end thereof and arranged to provide a shell-like structure the interior of which is unobstructed and free to contain gas cells and facilitate handling thereof, said articulated composite beams being composed of a succession of rigid members having means providing outwardly facing plane surfaces at opposite ends thereof and flexibly connected together between such surfaces by means capable of absorbing tension, compression and torsional stresses whereby stresses and strains received by the beams are transmitted and distributed through the rigid members composing the same

and absorbed and spent in said connecting means.
7. A framework for airships including a plurality of articulated composite beams extending in the surface of the framework from end to end thereof and arranged to provide a shell-like structure the interior of which is unobstructed and free to contain gas cells and facilitate handling thereof, said articulated composite beams being composed of a succession of rigid members

flexibly connected together between adjacent ends by means capable of absorbing tension, compression and torsional stresses whereby stresses and strains received by the beams are transmitted and distributed through the rigid members composing the same and absorbed and spent in said connecting means. 5
